UNITED STATES PATENT OFFICE.

DONALD S. VAN WAGENEN, OF BROOKLYN, NEW YORK, ASSIGNOR, BY MESNE ASSIGNMENTS, OF ONE-HALF TO BENJAMIN F. WATKINS, OF PHILADELPHIA, PENNSYLVANIA.

GRATE STRUCTURE.

Application filed August 5, 1921. Serial No. 490,063.

My invention relates to grate structures of the type forming the subject of my co-pending application, Serial Number 447,199, filed February 23, 1921, the object of the 5 present invention being to provide means whereby a superior distribution of the air through the hollow burners is obtained, with a consequent material increase in the efficiency of the grate.

10 With this object in view, I have designed, combined and arranged the several parts hereinafter more fully disclosed and illustrated in the accompanying drawings, in which:

15 Figure 1, is a transverse section of the fire-box of a boiler equipped with a grate structure made in accordance with my invention, and

20 Fig. 2, is a sectional view taken on the line 2—2, Fig. 1, illustrating the manner in which the air is introduced into the hollow grate bar sections from the expanding chamber.

25 In its preferred embodiment, my invention comprises a series of hollow grate bars or burners 1 which are mounted in the fire-box of a boiler to constitute the fuel-supporting bed, there being provided means for introducing air into the interior of the hollow grate bars, which latter are provided in

30 their upper wall with suitable slots or openings through which the said draft air passes, the air in this manner being distributed over the entire area of the fuel bed. In the present instance, I have illustrated the bars 1 supported at the front of the boiler upon an angle beam 2, and at the rear by the bridge wall 3, which latter is made hollow, the rear ends of the burners being open and

35 being inserted through suitable apertures 4 in the side of the bridge wall, whereby the burners are made to communicate with the chamber 5 in the interior thereof. The extremities of the bar being fixed, it is necessary to provide means intermediate the ends to take up the expansion in the bar, and this is accomplished in the present instance by making the body of the bar in two sections with one telescoping within the other.

40 I have discovered that in grate structures of this nature, where a plurality of independent burners or bars are fed with air from a single source, the distribution of the air among the bars is greatly improved

bars a chamber from which the air is taken by the bars through uniform openings. The chamber should be of such size and the admission and exhaust openings so disposed that none of the air forced into the chamber 60 can pass in a direct current to the exhaust openings, and with this in view, it is preferred to locate the exhaust openings out of the line of the current of air projected into the chamber through the admission opening. 65 Under these circumstances it has been found that the air instead of being driven directly into the bars or burners, which invariably results in an uneven distribution both to the individual bars and to the openings in 70 the fuel supporting wall within the bars, expands into the bars from the chamber with a substantially even distribution, and that furthermore the distribution within the bars to the openings in the upper wall is greatly 75 improved. I have further discovered that with the above described construction, the draft may be controlled more satisfactorily than with other systems since the air is distributed evenly to the bars entirely regardless of the amount of air entering the chamber or the force with which it enters.

80 It is preferable to place the source close to the chamber and to make any duct leading from the source to the chamber increasing in cross sectional area toward the chamber. It is further desirable to reduce the length of the ducts between the chamber and the bars to a minimum, the ideal arrangement being the entire elimination of connecting ducts by making the exhaust openings of the chamber the intake openings of the bars.

85 As clearly illustrated in the drawings, I form the space 5 within the bridge wall of 90 such size as to constitute the chamber, the draft air being conducted through a duct 6 from a suitable source, such as a blower 7, said duct increasing in area from the blower to the chamber.

95 It will be noted that the hollow grate bars are entirely open at one end and that this open end is inserted in openings in the side of the bridge wall. There is as a result no restriction of the air in passing into the bars from the chamber, the air passing with uniform velocity into the bars and filling the entire interior thereof at a substantially uniform pressure. There results a practically even flow of air through the top openings of 100 105 110

the bar from end to end with a corresponding even nourishment of the burning fuel over the entire bed area.

I have further discovered that by enlarging the chamber within the bridge wall in a rearward direction to obtain the desired capacity and by making the top wall over the chamber as thin as is practicable, there is obtained a very marked preheating effect on the air in the chamber, this being due to the heat conducted through the top of the bridge wall from the hot gases and flame which passes over the surface. The benefits of preheated air in this connection are well understood and the arrangement provides a distinct improvement over other grate structures of this type in which the preheating effect is not obtainable.

I do not desire to restrict my invention to any particular form of hollow burner, but the burner described in my aforesaid co-pending application is the best form of hollow burner, since it gives a greater active grate surface, is more economical to construct and maintain, and easier to install. 25

I claim:

A grate structure comprising in combination a hollow grate bar having openings in the upper surface thereof, an expansion chamber having unrestricted communication with the interior of the bars, air driving mechanism, and a duct establishing communication between said chamber and air driving mechanism and increasing in cross sectional area toward the chamber. 30

DONALD S. VAN WAGENEN.
